United States Patent Office.

FREDERICK M. HICKMAN, OF ROLLING PRAIRIE, INDIANA.

Letters Patent No. 76,190, dated March 31, 1868.

IMPROVEMENT IN GATES.

The Schedule referred to in these Letters Patent and making part of the same.

TO ALL WHOM IT MAY CONCERN:

Be it known that I, FREDERICK M. HICKMAN, of Rolling Prairie, in the county of La Porte, and State of Indiana, have invented a new and useful Improvement in Gates; and I do hereby declare that the following is a full, clear, and exact description of the same, reference being had to the annexed drawings, making part of this specification, in which—

Figure 1 is a front view, with the gate lowered; and

Figure 2 is a front view, with the gate elevated.

My improvements relate to that class of gates which may be elevated by the means of a lever, to allow hogs and smaller animals to pass under, and to swing clear and free from snow.

In the drawings, A is the gate, which is attached to the post B by the hinges C C, which hinges C C are constructed of round rod-iron, bent and attached to post B by nut on opposite side, to which the gate A is attached by bolt, with round hole, to slide up and down upon the hinges C C, and which form a part of said hinge C C, and which are attached to the gate A near the top and bottom rail of said gate A. The part of said hinges C C is so constructed in length that the gate A may be elevated just the length of the hinges C C. Thus, if you wish to construct your gate A so as to elevate it two feet, the length of your hinges C C must be just two feet.

D is the lever, to which is attached, between the second and third rail of the gate A, an iron rod, at the end of which is attached a chain or rope, which works under the pulley E, and is attached to the lower part of the upper hinge C, so that, when the gate A is elevated, the entire weight rests upon the chain or rope. The gate A is elevated or lowered with perfect ease, by drawing the lever D forward or letting it back.

The lever D may be fastened, either at the top or bottom, just as desired, and will work equally as well either way. The gate A may be elevated to any height desired, by catches on the gate A, to rest the lever D, and may be swung free from snow or other obstacles.

What I claim as my invention, and desire to secure by Letters Patent, is—

The combination of the hinges C C, lever D, and pulley E, respectively, constructed and arranged substantially as set forth.

In testimony whereof, I have signed my name to this specification in the presence of two subscribing witnesses.

F. M. HICKMAN.
